BINARY ELECTRO-MECHANICAL TRANSDUCER
USING A LATERALLY SLIDING ARMATURERanald O. Whitaker, 3145 N. Delaware,
Indianapolis, Ind. 46205
Filed Dec. 5, 1966, Ser. No. 599,038
2 Claims. (Cl. 335—170)

This invention relates primarily to binary or "flip-flop" relays. Such relays close electrical contacts upon receipt of one electrical signal and open the contacts upon receipt of the next electrical signal. More particularly this invention relates to the electro-mechanical arrangement for effecting this binary action.

In accordance with the invention the armature of a conventional relay is adapted to slide on its mounting so that it can rotate laterally through a small arc. This permits the head of the armature to move left and right. On the first activation of the magnet a lever catches on a first protruding lip and causes the armature to move to the left. The armature then comes to rest against a first contact. Upon the second activation the lever catches on a second protruding lip and causes the armature to slide to the right. The armature then comes to rest against a second contact.

A binary relay of conventional design requires one or two watts of electrical power for operation. A prime application for such relays is in remote controls for TV receivers. The receivers of such controls are generally transistorized. However, the output transistors generally deliver only 0.1 watt. In the usual system this 0.1 watt is used to drive a pilot relay which applies 110 volts to a conventional binary relay. A binary relay fabricated in accordance with the present invention can be operated directly from the 0.1 watt delivered by the transistor. Consequently this new relay may be used to replace the two-relay combination presently being used.

It is the object of the present invention to provide a binary relay directly operable from the 0.1 watt output of a transistor—thereby avoiding the need for a pilot relay to operate a heavier binary relay of conventional design.

Referring to the drawings:

FIG. 1 is a perspective drawing of a binary relay fabricated in accordance with the present invention.

FIG. 2 is a side view of a relay fabricated in accordance with the present invention.

FIG. 3 is a partial frontal view of the switching mechanism of a relay fabricated in accordance with the present invention.

FIG. 4 is a partial view of an alternate configuration of a relay fabricated in accordance with the present invention.

Referring to FIG. 1, a base 2 has fixed to it an electromagnet 4, a header 6 of electrically insulating material, and a tailpiece 8. Armature 10 of magnetic material rests in the recessed portion of tailpiece 8. Slots 102 and 103 of armature 10 are wider than the thickness of tailpiece 8. This permits armature 10 to tip forward and backward in a vertical plane and to rotate slightly in a horizontal plane. Shaft 12 is rotatably mounted in holes in the two upright portions of armature 10. Lever 14 is fixed to the forward end of shaft 12. Header 6 carries at its upper corners electrical contacts 16 and 18. It also carries posts 20 and 22.

Armature 10 is biased counterclockwise by spring 24 as indicated in FIG. 2.

Returning to FIG. 1, lever 14 carries four notches in its upper edge. The alignment of these notches with the contacts determines the particular binary position. For the position of parts shown in FIG. 1, lever 14 rests against contact 18, completing an electrical circuit from contact 18 to the frame of the relay. Lever 14 rests against post

2

20 and does not touch contact 16. The binary position illustrated by FIG. 1 is that in which an electrical circuit is complete to contact 18. It is apparent that armature 10 may be moved to the left so that lever 14 rests against contact 16 and stop 22. Contact 18 would be isolated. This position of the parts defines the second binary position.

How lever 14 is moved from the first binary position to the second binary position may be best understood by referring to FIG. 3. At the next activation of magnet 4, shaft 12 and lever 14 move downward. Tip 141 engages lip 61 of header 6. Tip 142 passes to the right of lip 62. A mechanical moment is produced which causes lever 14 to rotate counterclockwise with tip 141 as a center. This rotation causes armature 10 to move sideward in the direction of contact 16. Armature 10 rotates on tailpiece 8. The system is arranged so that motion ceases with slot 30 directly under contact 16, slot 28 under stop 20, and slot 24 under stop 22.

When magnet 4 releases, armature 10 moves upward carrying shaft 12 and lever 14. Lever 14 comes to rest against contact 16 and stop 22. This is recognized as the second binary position.

A similar action involving tip 142 and lip 62 takes place upon the next activation of magnet 4. The system is returned to the first binary position. Slot 26 comes to rest under stop 22 and slot 24 comes to rest under contact 18.

The slots serve as indexing devices which cause the downward motion of lever 14 to start precisely from one of the two binary positions. Consequently lever 14 always strikes the appropriate lip of header 6. It never strikes both lips or misses both. It cannot "hang-up" in mid-position. Contacts 16 and 18 and stops 20 and 22 have been shown rounded. They may be pointed to match the slots.

The relay as described closes the electrical contacts during the magnet-off period. Generally, relays close the electrical contacts during the magnet-on periods. It is apparent that placing contacts on lips 62 and 61 converts the relay into a unit which closes the electrical circuits during the magnet-on periods.

It is also apparent that the structure thus far described may be inverted so that the indexing notches close to their stops upon activation of the magnet and lever 14 strikes the lips upon magnet deactivation.

Many variations are possible. In particular, the electrical contacts may be separated from the indexing system. Typical of such systems is that shown in FIG. 4. A plate 32 of insulating material and fixed to the frame of the relay carries on its lower surface contacts 34 and 36. Lever 14 carries contact 38 along its upper edge. Shift of lever 14 back and forth between its two binary positions moves contact 38 back and forth between contacts 34 and 36. This system has the advantage that conventional electrical contacts may be used. Also, only three contacts are needed. It has the disadvantage that careful alignment of the three contact points must be effected.

The main use of the subject invention will be in the operation of the contacts of binary relays. However, the invention may be used in many other applications. It may be used to interrupt a light beam upon reception of each second electrical signal. The light beam may be replaced by a jet of air or of water. The subject invention is essentially the provision of an electrically driven binary mechanical device. The invention centers on the mechanism for causing the lateral movement of the armature from one binary position to the other.

I claim:

1. An electro-mechanical transducer comprising a frame bearing an electromagnet; an armature assembly having an armature adapted to be drawn by said electro-

magnet and a lever having notches along one edge said lever being rotatably mounted to said armature; and stops fixed to said frame and adapted to fit into said notches in two different combinations, the first of said combinations defining a first binary position, the second of said combinations defining a second binary position; said lever having a first corner which upon movement of said armature away from said stops when said armature is in said first binary position engages a first lip of said frame, said engagement causing lateral movement of said armature to said second binary position; and said lever having a second corner which upon movement of said armature away from said stops when said armature is in said second binary position engages a second lip of said frame, said engagement causing lateral movement of said armature to said first binary position.

2. An electro-mechanical transducer as in claim 1, and having one or more electrical contact pairs, one contact

of each pair being associated with said armature assembly and one contact being associated with said frame, one or more of said contact pairs closing when said armature is in said first binary position and opening when said armature is in said second binary position, the remainder of said contact pairs closing when said armature is in said second binary position and opening when said armature is in said first binary position.
